ABSTRACT

An improved pump filter for a recirculating toilet system includes a one-piece elastomeric diaphragm that is retained by a cover plate which is captured by a yieldable clamping ring. Normal pump operation is achieved through application of a pneumatic fluid such as compressed air. Potentially dangerous pressure excesses between the cover and the diaphragm can escape when the clamping ring holding forces are exceeded, and excess pressures tend to increase pressure to the "O" ring seal section thereby improving the liquid seal while relieving the excess or overpressure as the cover plate clamping ring yields in the preferred direction. A bead on the diaphragm periphery functions as an "O"-ring seal when the pump is mounted below the waste tank.

DIAPHRAGM PUMP FOR A RECIRCULATING TOILET

The present invention relates to a recirculating sanitary system, and, more particularly, to an improved pneumatic filter pump for providing filtered flushing liquid, to a toilet.

In the patent to James M. Kemper, U.S. Pat. No. 3,567,032, issued Mar. 2, 1971, and assigned to the assignee of the present invention, a filter and pump for a recirculating sanitary system was shown which was adapted to be placed wholly within the storage tank of the sanitary system and was, in the preferred embodiment, operated by a pneumatic system. Because the filter pump was intended to operate immersed in the storage tank, the apparatus was enclosed in mating members which were sealed at a peripheral flange. A diaphragm member was captured within the flange and defined driving and driven portions of the pump. Pneumatic "fluid" was applied to the driving side of the pump and filtered flushing liquid was stored and applied to the toilet bowl from the driven side.

More recently, a patent issued to James M. Kemper on Jan. 18, 1972, U.S. Pat. No. 3,634,891 and assigned to the assignee of the present invention, which disclosed a similar concept. A first embodiment included a diaphragm pump driven by a pneumatic system and an alternative configuration showed a diaphragm pump, which was mounted on the exterior base of the storage tank, and which was driven by a pedal member (of FIG. 18 of the patent).

The present invention concerns an improved filter pump which, in the preferred embodiment, is also pneumatically operated and which is also intended to be mounted to the outside of the underside of a storage tank in a recirculating sanitary system. According to the present invention, an improved diaphragm has been designed which is intended to overlap a pump base plate and provide an o-ring seal against the bottom of the tank. A plastic cover is clamped against the diaphragm of the opposite side of the base plate in a yieldable seal, which is held by a peripheral, resilient clamping ring.

When the hydraulic pressure between the plastic cover and the diaphragm exceed the ambient pressure by a predetermined safe level, the holding ring has sufficient elasticity to permit an escape of pneumatic fluid from between the diaphragm and the cover while still maintaining a fluid-tight seal between the base plate and the tank. Further, any leakage of flushing liquid from the pump would tend to be directed into the tank since the peripheral bead of the diaphragm functions as an o-ring seal.

An improved filter plate and comb combination is provided which is easily installed and removed from the base plate using a plastic, interrupted flat-washer, which retains the filter plate in a recess that is provided for it.

The present invention is deemed to have specific utility in vehicles which have a ready supply of pneumatic fluid available, such as busses and trains. The device is easily modified for hydraulic operation, as well. A pneumatically or hydraulically operated device is preferable to an electrically powered system in such an environment since personnel trained to handle pneumatic or hydraulic systems are far more available than persons trained to handle electrically operated systems.

The novel features which are believed to be characteristic of the invention, both as to organization and method of operation, together with further objects and advantages thereof will be better understood from the following description considered in connection with the accompanying drawings in which several preferred embodiments of the invention are illustrated by way of example. It is to be expressly understood, however, that the drawings are for the purpose of illustration and description only and are not intended as a definition of the limits of the invention.

FIG. 1 is a side view, partly in phantom of a recirculating sanitary system incorporating an improved filter pump according to the present invention;

15 FIG. 2 is a top view, partly broken away of an improved filter pump according to the present invention, taken along line 2-2 of FIG. 1 in the direction of the appended arrows;

20 FIG. 3 is a side sectional view of an improved filter pump of FIG. 2 taken along the line 3-3 in the direction of the appended arrows;

25 FIG. 4 is an enlarged side sectional view of the mounting flange shown in FIG. 3 and identified as Section 4-4; and

30 FIG. 5 is an enlarged sectional view of the retaining flange of FIG. 4 yielding to relieve excess pneumatic pressure within the pump of the present invention.

Turning first to FIG. 1, there is shown a typical recirculating sanitary system 10, including a toilet 12, a tank 14, and a pump 16. The pump 16 operates in response to applied pneumatic fluid such as compressed air in the preferred embodiment to pump filtered flushing liquid through the toilet 12. On a return "stroke" pump 16 fills with a charge of fluid that is filtered from the tank 14. As shown, the toilet is provided with a decorative access cover for a drain valve 18 and further includes a lid 20 and a seat 22.

Indicated in phantom view is a flush outlet line 24 which conveys flushing liquid to the toilet bowl. A pneumatic input line 26 applies pneumatic fluid to the driving side of the pump 16. For the detailed construction of the toilet itself, reference is made to the Katona U.S. Pat. No. 3,256,221, *supra* and the Kemper U.S. Pat. No. 3,634,891.

45 As shown in FIG. 2, the pump 16 includes a flushing fluid outlet port 28 which connects to the flush line 24. An apertured filter plate 30 cooperates with a comb member having a plurality of pins 32, to permit flushing liquid to pass from the tank 14 to the interior of the pump 16. As taught in the prior Kemper patents, the combination of the pins 32 and their associated apertures in plate 30, provides a restricted annular orifice which effectively prevents solid or particulate matter from passing from the tank 14 to the pump 16. A split washer member 34 similar to a circlip seats in a circumferential groove 36 to retain the filter plate 30 in place.

50 A pump base plate 38 holds the filter plate 30 and fits into an opening provided in the tank 14. A peripheral flange 40 fits snugly within an opening provided in the bottom 42 of the tank 14.

55 A diaphragm member 44 is made of an elastomeric material and is provided with a continuous peripheral bead 46. The diaphragm 44 is molded with a folded flange 48 at the periphery that encloses the base plate member 38, best seen in FIGS. 3-5, described below.

60 In FIG. 3, the structural details of the diaphragm pump 16 are shown more clearly. On the outer surface

at the bottom 42 of the tank 40, a peripheral groove 50 is provided to receive the peripheral bead 46 of the diaphragm 44. An o-ring seal is formed which tends to retain fluids within the tank 14.

A pump cover 52 serves to protect the diaphragm 44 and acts as the outer wall of the "driving" side of the pump 16. The cover terminates in a cover flange 54 which bears against the diaphragm folded flange 48, the edge of the base plate 38, and the exterior surface of the tank bottom 42. The inner surface of the cover flange 54 is provided with a series of vestigial ribs 56 which help grip and hold the folded flange 48. A peripheral ridge 58 cooperates with a flexible metallic holding ring 60 to maintain the cover 52 in a sealed relationship with the exterior of the tank 12, thus providing a fluid tight volume for driving the pump 16.

A heavy duty return spring 62 is provided to aid in the exhaust of the driving fluid and to provide an intake stroke for the pump operation when the flushing action is completed. A rigid plastic spring support member 64 protects the diaphragm 44 from the return spring 62. The return spring 62 and spring support member 64 urge the diaphragm 44 to the full open position. A unidirectional intake flow valve 66 and a unidirectional outlet flow valve 68 enable the driven side of the pump to fill during the intake stroke and to discharge the filtered flushing liquid into the flush outlet line 24 when driving fluid is applied to the volume between the diaphragm 44 and the pump cover 52.

The filter pins 32 are formed as an integral part of a filter comb assembly 70 which is mounted in a recess 72 that is provided in the base plate 38. A stem element 74 includes a shoulder portion 76 which rests against an opening 78 in the filter recess 72. The stem 74 extends into the driven chamber and contains a bias spring 80 which holds the filter in a retracted position.

A reinforced strike plate 82 in the spring support member 64 moves the stem 74 and the comb assembly 76 when the driving fluid is applied to the pump and the support member 64 is driven toward the base plate 38. The return spring 62 is positioned to surround the "exterior" of the filter recess 72.

The diaphragm 44 includes a thickness ring 84 which spaces the diaphragm 44 away from the inner wall of the pump cover 52. The thickened ring 84 limits the travel of the bias spring 62. An alternative configuration of the diaphragm 44 in the driving stroke is indicated in the dashed outline. A driving fluid input line is provided but not shown.

The metallic holding ring 60 is fastened to a mounting ridge 86 with a plurality of screws 88 which, when secured, applies a compressive force to the cover flange 54. The compressive force acts to create fluid-tight seals on both the driving and driven sides of the pump.

In operation, pneumatic driving fluid under pressure is applied to the driving side of the pump. As the pressure builds, the fluid applies a force to the diaphragm 44 which overcomes the resistive force of the return spring 62. The diaphragm 44 moves upward, (as seen in FIG. 3) until the strike plate 82 engages the stem 74. As the volume in the driven side decreases, filtered flushing fluid is forced out through the valve 68.

At the end of the driving stroke, the stem 74 forces the filter comb assembly 70 and the pins 32 through the apertures in the filter plate 30. The fully compressed return spring 62 and the spring support member 64 de-

termines the extent of diaphragm 44 travel during the driving stroke.

Once the pressure of the driving pneumatic fluid is released, the return spring 62 urges the diaphragm downward (as viewed in FIG. 3). The bias spring 80 retracts the filter comb assembly 70 as fluid is drawn into the driven side of the pump through the filter and the intake valve 66. The rate at which the pump fills with filtered liquid is determined by the return spring 62 and by the rate at which the pressure is relieved.

Turning next to FIG. 5, there is illustrated the manner in which the differential in pressure as between the interior of the driving side of the pump and ambient in excess of what might be considered a safe level is relieved. The excess pressure in the interior is vented to ambient while maintaining a fluid tight seal of the tank and its contents by applying a force against the metal holding ring 60. As shown, the pneumatic fluid escapes between the folded flange 48 of the diaphragm 44 and the ribs 56 of the cover flange 54.

Thus there has been shown an improved, pneumatically operated recirculating toilet which includes a novel diaphragm member, that also functions as a sealing gasket. Further, the diaphragm is provided with a peripheral bead which functions as an O-ring seal.

A molded cover bears against the diaphragm and defines the "driving" side of the pump. The cover is held in place by a flexible retaining ring, which is prestressed to maintain a fluid-tight seal between the cover and the diaphragm. When excess pressure builds in the driving side of the pump, the retaining ring will, under such excess pressures, yield to permit the escape of pneumatic fluid between the cover and the diaphragm. The pneumatic fluid, acting upon the diaphragm, maintains a firm seal on the driven side of the pump and prevents the escape of any material from the driven side.

Other modifications and embodiments will be obvious to those skilled in the art and, accordingly, the scope of the invention should be limited only by the claims appended hereto.

What is claimed as new is:

1. A diaphragm pump including:

- a diaphragm member having an enlarged neck portion adjacent the periphery, said neck portion being adapted to receive a plate member;
- a cover portion, including a flange adapted to seat against said neck portion and plate member, capturing a part of said neck portion therebetween to produce a fluid-tight seal; and
- a flexible retainer ring member mounted adjacent said cover portion and prestressed to apply a seating force on said flange, said cover portion and ring member responding to driving fluid pressures between said cover portion and said diaphragm member that are greater by a predetermined amount than said seating force, to unseat said cover portion for relieving excess driving fluid pressures.

2. The diaphragm pump of claim 1, above, wherein said diaphragm member has a bead at the peripheral edge thereof and said bead is adapted to function as an O-ring when said cover is seated.

3. The diaphragm pump of claim 1, above, wherein the surface of said cover portion flange adapted to bear against said diaphragm member includes a plurality of ribs for improving the seal between said flange and said diaphragm member.

4. For use in combination with a recirculating toilet having a storage tank, a diaphragm pump adapted to be mounted in fluid communication with the storage tank comprising, in combination:

- a. a diaphragm member having a peripheral edge and an elongated, fluid-receiving interior portion and an enlarged neck portion adjacent said peripheral edge;
- b. a filter plate member adapted to be inserted into said enlarged neck portion to provide, in combination with said diaphragm member, upper and lower sealing surfaces, said filter plate member including means for filtering the contents of said storage tank to provide flushing fluid;
- c. a cover member having a peripheral flange adapted to fit against one of said sealing surfaces to

create a driving chamber between said cover member and said diaphragm member; and

- d. flexible retainer ring means mounted to the storage tank, including a ring member adapted to fit over said cover member flange, said ring member being prestressed to apply a sealing force against said flange, said neck portion, said filter plate member, and the outer surface of the storage tank to provide fluid-tight seals for retaining driving fluid and flushing fluid,

whereby excessive driving fluid pressure can overcome the force of said ring member to permit driving fluid leakage between said diaphragm member and said cover member.
